UNITED STATES PATENT OFFICE.

ABNER J. WINDER, OF FRESNO, CALIFORNIA.

HINGE.

Specification of Letters Patent. Patented Mar. 21, 1916.

1,176,121.

Application filed June 1, 1915. Serial No. 31,359.

To all whom it may concern:

Be it known that I, ABNER J. WINDER, a citizen of the United States, residing at Fresno, in the county of Fresno and State of California, have invented new and useful Improvements in Hinges, of which the following is a specification.

This invention relates to a hinge and particularly pertains to a spring hinge for normally maintaining the closure to which it is attached in a closed position.

It is the object of this invention to provide a hinge of the above character having a demountable pivot pin whereby the leaf members of the hinge may be separated when it is desired to remove the door or closure carried thereby without detaching the leaf members of the hinge from the closure or its casing.

Another object is to provide a construction whereby the pivot pin will serve as a fastener for holding one end of the hinge spring against movement and by which the pull on the spring will be transmitted to one of the hinge leaf members through the removable pivot pin.

Another object is to provide a removable pivot pin for spring hinges so formed and mounted that it may be readily removed and replaced and whereby it is rigidly held against turnable movement in relation to one of the hinge leaf members.

A further object is to provide a spring hinge having a demountable pivot pin and separable leaf members with an adjustable helical spring arranged to normally dispose the hinge leaf members in a closed position, which embodies few parts adapted to be readily assembled and demounted.

The invention is illustrated in the accompanying drawings in which:

Figure 1 is a view in perspective illustrating the hinge as applied to a door and its casing. Fig. 2 is a view of the hinge as disposed in an open position showing it partly in vertical section and partly in elevation with portions broken away. Fig. 3 is a view in horizontal section on the line 3—3 of Fig. 2 showing the hinge leaf members as positioned at right angles to each other. Fig. 4 is a view in enlarged horizontal section on the line 4—4 of Fig. 2. Fig. 5 is a view in enlarged horizontal section on the line 5—5 of Fig. 2. Fig. 6 is an enlarged detail section on the line 6—6 of Fig. 2. Fig.

7 is a view in perspective of the demountable pivot pin.

More specifically, 10 indicates one of the leaf members of the hinge which is formed with a cylindrical casing 11 on one edge thereof, the casing 11 being open at its upper end and having an inturned annular flange 12 on its lower end. The casing 11 is preferably formed of a length less than the length of the leaf member 10 and arranged thereon with its upper and lower ends spaced from the upper and lower edges of the leaf member.

The casing 11 is designed to receive a helical spring 13, the lower end of which is engaged by a collar 14 having a diameter slightly less than the inside diameter of the casing and adapted to be positioned within the latter and to seat on the flange 12. The collar 14 is formed with an opening having a flat face 15 and which opening is here shown as semi-circular in form with its arcuate portion in vertical alinement with the inner marginal edge of the flange 12. The upper end of the spring 13 engages a sleeve 16 having an outwardly extending shoulder 17 adapted to seat on the upper end of the casing 11; the sleeve 16 thus having a lower portion of one diameter to extend within the casing in slidable contact therewith and having an upper portion extending above the casing. The lower portion of the sleeve is formed with an annular channel 18 which is engaged by a set screw 19 extending through the wall of the casing 11 by which the sleeve 16 is held in position on the upper end of the casing. The upper portion of the sleeve is formed with a series of sockets 20 on its peripheral face for the reception of a pointed instrument (not shown) by which the sleeve may be rotated to adjust the tension of the spring 13; the sockets 20 also serving as depressions to receive a demountable pin 21 arranged to extend outwardly from the sleeve 16 into engagement with the leaf member 10 to hold the sleeve 16 against rotation and to retain the spring 13 under tension. The other leaf member 22 of the hinge is formed with a pair of spaced lugs 23 and 24 on one edge thereof which lugs are arranged such distance apart that the upper face of the lower lug 24 will abut against the under side of the casing 11 and the lower face of the upper lug 23 will be disposed against the upper face of the sleeve 16 when

105

110

the leaf members of the hinge are joined together, as shown in Fig. 1. The upper lug 23 is formed with a vertical bore 25 which is preferably circular in form for the reception of a demountable pivot pin 26 which is designed to extend through a circular opening 27 in the sleeve 16 and to project through the collar 14 and the lower end of the casing 11 into a recess 28 formed in the lower lug 24. The upper end of the pivot pin 26 is formed with a head 29 adapted to seat on the lug 23 and the lower end of the pivot pin is formed with a flat face 30 adapted to engage the flat face 15 forming one wall of the opening through the collar 14 and to also engage a corresponding flat face 31 forming one wall of the recess 28. When the hinge is assembled and the pivot pin 26 is in position, as shown in Fig. 2, the lower end of the pivot pin will be engaged by the lug 24 so that the pin will be held against rotation in relation to the leaf member 22 and the lugs thereon and the collar 14 will be engaged by the pin and held against rotation in relation to the pin and the leaf member 22; the leaf member 10 being pivoted on the pivot pin 26 to turn in relation to the leaf 22.

The lower portion of the pin 26 may be of any desired shape, the essential feature being to provide it with a flat face by which it will engage corresponding faces on the collar 14 and lug 24 but it is preferably formed of semi-circular cross section with its arcuate face arranged to slidably contact the inner peripheral face of the flange 12 to form a lateral bearing for the casing 11.

In the application and operation of the hinge, the spring 13, collar 14 and sleeve 16 are placed in position in the casing 11. The lugs 23 and 24 are then disposed astride of the casing 11, whereupon the pivot pin 26 is introduced through the opening 25 in the lug 23 and passed through the sleeve 16 and the collar 14 axially of the spring 13 into engagement with the lug 24, as shown in Fig. 2. The spring 13 is then tensioned by rotating the sleeve 16 by a suitable implement and when the desired tension is obtained the pin 21 is inserted in the socket 20, as shown in Fig. 3, to retain the spring under tension. The leaf members 10 and 22 may then be attached to a casing 32 and a door 33 by means of screws 34 or other suitable fastenings, as shown in Fig. 1, or the leaf members may be separated and secured in place on the casing and door before assembling.

When it is desired to demount the door 33 the spring 13 is untensioned by removing the pin 21, whereupon the pivot pin 26 may be withdrawn, thus separating the leaf members 10 and 22 of the hinge, thereby permitting the removal of the door without detaching the leaf members from the casing and door.

I claim:

1. A spring hinge comprising a pair of leaf members, a casing on one of said leaf members, a sleeve revolvably mounted in one end of said casing and held against withdrawal therefrom, a helical spring within said casing having one end attached to said sleeve, spaced lugs on the other leaf member one of which extends against one end of the casing and the other of which extends against the end of the sleeve, a removable pivot pin extending through one of said lugs and through the sleeve and the casing in turnable relation thereto, and held against movement in the other lug, means slidably engageable with the pin in which the other end of the helical spring is attached, and means for locking the sleeve in various positions against movement in relation to one of the leaf members.

2. A spring hinge comprising a pair of leaf members, a cylindrical casing on one of said leaf members, a sleeve mounted on one end of said casing and extending thereto, having an annular groove, a pin on said casing slidably engaging the groove, a helical spring within the casing having one end affixed to the sleeve, spaced lugs on the other leaf member arranged with one lug abutting against one end of the casing and the other lug abutting against the sleeve, a pivot pin extending through one of the lugs and projecting through the sleeve and the casing in turnable relation thereto and held against rotation in the other lug, means slidably engaging the pin to which the other end of the helical spring is attached, and means for holding the turnable sleeve against rotation in relation to the cylinder carrying leaf member.

3. A spring hinge comprising a pair of leaf members, a demountable pivot pin connecting said leaf members having a flat face engageable with the corresponding face on one of the leaf members, a collar formed with an opening through which the flat portion of said pivot pin extends to hold the collar against rotation, a spring wound around the pivot pin having one end engaged by said collar, a turnable sleeve on said pivot pin to which the opposite end of the spring is attached, and means for holding said sleeve against movement in relation to one of the leaf members.

4. A spring hinge comprising a leaf member, a cylindrical casing on said leaf member, a turnable sleeve on one end of said casing, a second leaf member having spaced lugs thereon, a collar in said casing, a helical spring having one end attached to said collar and its opposite end secured to the turnable sleeve, and a demountable pivot pin connecting the spaced lugs and extending through the sleeve, casing and collar formed with a flat face engageable

with corresponding faces in the collar and the lowermost lug, whereby the pin and collar are held against rotation.

5. A spring hinge comprising a leaf member, a cylindrical casing on said leaf, a turnable sleeve on one end of said casing, a collar in said casing, a helical spring having one end attached to said collar and its opposite end secured to the turnable sleeve, 10 a second leaf member having spaced lugs at its upper and lower ends, a demountable pivot pin connecting the spaced lugs and extending through the sleeve, casing and collar, and means on the pin co-operating 15 with the lowermost lug and the collar, whereby the pin and collar are held against rotation.

6. A hinge comprising a leaf member, a tubular casing on said leaf member, an in- 20 turned flange formed on the lower end of said casing, a collar supported on said flange within the casing in turnable relation to the latter formed with an opening having a flat wall, a sleeve turnably mount- 25 ed on the upper end of said casing having a circular opening therethrough, a helical spring arranged within the casing having one end attached to the collar and its opposite end attached to the sleeve, means for 30 holding said sleeve against movement in

relation to said leaf member, a second leaf member, a pair of spaced lugs thereon, one of said lugs having a circular opening therethrough and the other lug having a recess formed with a flat wall, and a de- 35 mountable pivot pin adapted to extend through the circular openings in the lug and the sleeve formed with a flat face engageable with the flat walls in the collar and the other lug. 40

7. A spring hinge comprising a pair of sleeve members, a demountable pivot pin connecting said sleeve members and held against rotation in relation to one of the sleeve members, a helical spring surround- 45 ing the pivot pin, a turnable sleeve encircling the pivot pin to which one end of the spring is attached, means for locking the sleeve against movement in various posi- 50 tions in relation to one of the leaf mem- bers whereby tension of the spring may be adjusted, and a collar encircling the pivot pin to which the other end of the spring is attached; said collar being slid- 55 ably connected to said pin but held against rotation in relation thereto.

In witness that I claim the foregoing I have hereunto subscribed my name.

ABNER J. WINDER.
